CATHETER

Paul A. Raiche, North Providence, R. I., assignor
to Davol Rubber Company, a corporation of
Rhode Island

Application June 6, 1936, Serial No. 83,948

2 Claims. (Cl. 128—349)

This application is a continuation in part of application Ser. No. 49,055 filed November 9, 1935, for Construction of rubber articles.

My present invention relates to medical apparatus and has particular reference to catheters and other articles having inflatable walls.

It is the principal object of my invention to provide a rubber article of integral construction having an interior recess in the walls thereof, whereby part of the wall may be inflated if desired.

It is a further object of my invention to specifically apply the improved construction to a catheter, in order to obtain a retaining or internal treatment catheter having an integral inflatable bulb.

It is a further object of my invention to provide a novel construction for obtaining wall recesses in any dipped article without using separate article pieces which must be cemented together.

With the above and other object and advantageous features in view, my invention consists of a novel article, more fully disclosed in the detailed description following, in conjunction with the accompanying drawing, and more specifically defined in the claims appended thereto.

In the drawing, which shows the invention as specifically applied to a catheter,

Fig. 1 is a plan view of a novel catheter embodying the principle of my invention;

Fig. 2 is a section of Fig. 1 on the line 2—2 thereof;

Fig. 3 is a section on the line 3—3 of Fig. 2;

Fig. 4 is a section on the line 4—4 of Fig. 2;

Fig. 5 is a perspective view of a novel dip rod;

Fig. 6 is a perspective view of a novel wire form used in conjunction therewith;

Figs. 7, 8, 9 and 10 are sections showing the sequence of steps in manufacturing the novel catheter;

Fig. 11 is a perspective view showing an intermediate stage of construction;

Fig. 12 is a view, partly broken away, showing the completed novel inflatable portion as it appears when inflated; and

Fig. 13 is an enlarged sectional view of a modified construction providing a funnel inlet.

It has been found desirable to manufacture rubber articles, and particularly articles intended for medical and surgical use so as to provide an integral article having inflatable wall portions, the inflatable portions being independently controllable. For example, an internal treatment catheter requires a flow channel for the passage 55

of treating fluid, and is made with an inflatable bulb portion according to my invention, which permits an independent inflation of the bulb so as to retain the catheter in treatment position, and to permit use of the catheter as a yielding massage instrument or the like if desired. Catheters of this type have heretofore been made in several pieces which are cemented together, thus producing undesirable seams which hinder introduction of the catheter, in addition to the danger of the seams separating and coming apart.

I have therefore devised a method for manufacturing an integral, one piece bulb catheter, utilizing a dip form such as a rod 10, see Fig. 5, which has a longitudinal groove 11. This dip rod is dipped a predetermined number of times in latex, which may be prevulcanized or unvulcanized, to obtain a coat 12, see Fig. 8; a wire form 13, see Fig. 6, having a manually graspable bent end 14, and a bent end 15 which is breakable from the wire 13 at a point 16 of reduced area, is then positioned in the groove 11 over the latex formed therein, as indicated in Fig. 9, and held in place in any desired manner, as by thin spaced latex bands. The form and wire are then dipped again, whereby a thick coat 17, see Fig. 10 is formed, the form and coat at this stage of manufacture having the appearance shown in Fig. 11. A portion 18 of the coat of any suitable width such as indicated by the letter A is then painted with a local curing agent, such as a solution of sulphur chloride gas in alcohol or a solution of bromine gas in alcohol, the solution providing a surface cure for the painted portion 18. The article is then allowed to dry to facilitate handling; the end 15 is then broken off, and the dipping resumed to produce the completed catheter 19 shown in Figs. 1 and 2, the catheter being dried and then cured, the rod 10 and wire 13 then being withdrawn.

The completed catheter, see Fig. 2, thus consists of an elongated tube which has an integral independent passageway 20 formed in the wall thereof, the passageway 20 terminating between spaced walls 18 and 21 which provide a space or recess 22 therebetween due to the initial curving of the portion 18, whereby a bulb 23 is formed which may be inflated, as indicated in Fig. 12, by forcing air or other fluid under pressure through the passageway 20. An eye 24 is preferably formed in the catheter tip 25 between the end and the inflatable bulb at the end of the catheter, the eye communicating with the main catheter passageway 26. A small flexible tube 55 may, if desired, be used in place of the wire 13;

although a groove in the dip rod produces a more finished catheter, the groove may be omitted.

The above described construction thus produces a one piece, integral catheter having an inflatable bulb portion which has an independent fluid passageway, whereby control of inflation of the bulb, and use of fluids of different temperatures therein is independent of the use of the catheter and of the main catheter passageway. Catheters of the described type as previously made have had an inflating tube placed in the main passageway, thus reducing the flow area and restricting drainage.

It is desirable for certain uses to provide a funnel entrance to the passageway 20. This is readily accomplished by mounting a funnel or cone shaped member 27 on the end of the passageway wire form, see Fig. 13; the end is designated 28 and is preferably made longer than member 27 to receive the member 27, which slides over it to a point adjacent the linear central portion of the wire form, a kink 29 being provided near the inner portion of the end 28 to releasably lock the member in place. If desired, the free end of the end 28 may be made longer and bent over to twist around the rod 10, or to engage a hook placed thereon, so as to keep the end and the funnel shaped member seated thereon in fixed relation to the rod 10. The completed dipping of the catheter thus provides the end 30 with a boss having a funnel inlet for the bulb passageway.

The breakable end 15 may be omitted if desired; an opening for the end of the passageway 20 may then be made, after the local curing solution is applied to the portion A, by burning or otherwise cutting an opening through the locally treated portion, to the end of the wire form 13. After forming the opening, additional curing solution is applied to the formed opening, in order to prevent adherence of material during the final dipping which provides the final coating and the outer wall of the recess.

Although bromine in alcohol solution is suitable for the local curing, there is a slight tendency for vaporization of the bromine and a resultant migration of the bromine vapor, which tends to produce an irregular edge for the treated area. It is therefore preferred for certain constructions to mix talc with the bromine solution and thus form a flowing paste which can be painted on the selected local area without spreading. The process thus includes a painting with semi-liquid paste, which is allowed to remain in place for a sufficient time to obtain the local curing, and is then washed off; the surface is dried and is then ready for the final dipping.

Although I have described the invention is specifically applied to a retaining type catheter, it is obvious that the invention may be applied to any article which is made by dipping into a rubber or rubber like solution for producing a final article having a high degree of elasticity.

The preferred dipping solution is latex, which may be prevulcanized or nonvulcanized, but any material having similar characteristics may be used; the article is first formed to an intermediate stage, then a portion thereof is surface cured to prevent adherence, then the dipping is continued so to complete the article, whereby the completed article is an integral one piece article having an inner recess. The invention may be utilized for the manufacture of rubber articles in general, by dipping, surface curing, and then dipping again, to obtain one piece articles having inner chambers, recesses, passageways, or openings.

15 Although I have described the rubber articles as formed by dipping, any coating process may be used, the form being coated, then surface treated locally to prevent adherence over the treated area, and then coated again. Any coating material may thus be used to provide an integral finished product having inner recesses and the like. The surface curing agents are preferably in solution form, the halogen gases in alcohol being suitable for the described purpose,

25 but may be of other materials, either solid, paste, liquid or gaseous, having the property of producing a local surface curing.

While I have described a specific constructional embodiment of my invention, it is obvious that changes in the manner of forming, in the materials used for the article and for the dip solution, in the materials used for the local surface curing, and in the arrangement of the parts, for producing the desired completed internal recess and the formation of passageways leading thereto, may be made without departing from the spirit and the scope of the invention as defined in the appended claims.

I claim:

40 1. An integral one piece inflatable catheter having a bore and a wall recess spaced from the end, the wall of the catheter having a fluid passageway extending longitudinally thereof and communicating with said recess, the wall portion between the wall recess and the end having a discharge opening therethrough communicating with the bore, the catheter having a fluid inlet boss provided with a funnel shaped inlet communicating with said passageway.

45 2. An integral one-piece inflatable catheter including a tubular body member of soft rubber and substantially uniform external dimension from end to end of predetermined character to correspond with the orifice to be treated and having a bore and a wall recess spaced from one end, the wall of the catheter having a fluid passageway extending longitudinally thereof from the other end and communicating with said recess, the wall portion between the wall recess and the first mentioned end having a discharge opening therethrough communicating with the bore.

PAUL A. RAICHE.
